UNITED STATES PATENT OFFICE

RUDOLF PAWLICKOWSKI, OF GOERLITZ, GERMANY

MATERIAL-SHAKING MECHANISM

Application filed April 11, 1928, Serial No. 269,096, and in Germany February 10, 1928.

My invention relates to shaking devices for sifting and mixing purposes. In devices of this kind, it is well known that a reciprocating shaking motion is of advantage because each 5 time a reversal of motion takes place, relative movements occur in the sifting product or mixture itself as well as with respect to the receptacle, and these movements bring about an intimate mixing or rapid sifting. This 10 reciprocating motion however requires a special driving mechanism with crank or similar drive if the shaking device is to be operated from a rotating shaft. The drive becomes simpler when the receptacle containing the 15 product to be sifted or mixed is given a gyroscopic motion like a centrifugal apparatus, because then the rotary motion of the driving shaft need not first be converted into a reciprocating motion. The only thing to take 20 care of is that the product in the rotating container shall be given such movements with respect to itself and the said container, as are essential for intimate mixing and rapid sifting.

25 This is achieved by my present invention, which consists substantially in this, that the mixing or sifting container, or its carriage, which is pendulously mounted on a vertical rotating shaft, is provided with stops which 30 are arranged at the periphery of the container or its carriage, and are situated in a polygon, the said stops rolling round an enclosing ring with an impulsive jerking action together with the container, due to the oblique 35 position of the latter when rotating.

By way of further explaining my invention, I will now refer to the accompanying drawing which shows a preferred embodiment of my invention as applied to a shaking 40 machine for sifting boxes.

Figure 1 shows a partial vertical longitudinal section through the shaking machine.

Figure 2 is a horizontal cross section through line 2—2 of Fig. 1.

45 Figure 3 shows a detail partly in vertical section.

The machine framework *a*, preferably bell shaped, has a vertical revolving spindle *b*, which may be set into rotation by a crank handle *c* as well as from a machine drive *d*.

The hand drive *c* preferably engages with a catch in well known manner, on the vertical spindle *b*, the said catch being automatically disengaged when the machine drive is started. The lower end of the spindle *b* is provided with a suspension hook *e* from which is hung the holder for the sifting box. The hook *e* is suitably bent out to one side of the spindle so that the sifting box *g* is suspended laterally of the axis of rotation by the amount *s*. 55 The bell-shaped hood or cover of the machine framework *a* is furnished with one or more lateral openings *h* for inserting and withdrawing the sifting boxes. The holder for the sifting boxes consists of a supporting table *f* with two struts *i* which are connected at the top by a transverse yoke *j* which is provided with a suspension eyelet *k*. The struts *i* are furnished with threaded portions up and down which a clamping bar *l* may be moved by means of adjusting nuts *m*. The 60 sifting box *g* possesses several sifting compartments arranged above each other, *g*¹, *g*¹¹, *g*¹¹¹, *g*¹¹¹¹, with sifting meshes of different 65 fineness. They are so arranged that the fineness of the meshes increases from the coarsest one *g*¹¹¹¹ at the top to the lowest one *g*¹. At the periphery of the table *f* there are stops *n* which may consist of pins or bolts covered with rubber or any other shock absorbing 70 substance. Oppositethe stops *n* and level with them a striking ring *o* is arranged in the frame and this also may be covered with rubber or the like. 75

After a weighed quantity of powder, whose fineness is to be tested by sifting, has been deposited in the uppermost compartment, *g*¹¹¹¹ of the sifting box *g*, the latter is closed and placed on the table *f* through the opening *h*. The clamping bar *l* is screwed down 80 by means of the adjusting nuts *m* until it rests on the lid of the sifting box so that the latter is clamped in between the table *f* and the bar *l* and is thus fixed. Now after the vertical suspension spindle *b* has been set 85 into rotation either from *c* or *d*, the sifting box carriage along with the sifting box *g* swings outwards during the rotation, due to the centrifugal force and takes up the oblique position shown dotted in Fig. 1. In 90 95 100

so doing however, one of the stops *n* strikes against the encircling ring *o* so that the carriage is impeded in its regular rotary motion and is thrown off. It must then be accelerated afresh, whereupon it again assumes the oblique position until a stop again strikes the encircling ring and the action starts all over again. Each single stop *n* thus rolls round in the encircling ring *o* approximately in the form of the dotted curve *p* (Fig. 2). At each impact of the stops *n* with the ring *o* the product in the various compartments, is hurled apart and shaken, so that the same relative motions occur as with a reciprocating movement with a reversal of motion. The impulsive striking of the carriage against the encircling ring *o* may be accelerated or intensified, if, shortly before being started the box is pushed aside and is brought out of its regular rotary motion.

Owing to the oscillatory suspension of the sifting box carriage, the deflection, and consequently the checking impact is greater in the case of the lower disposed finer meshes than with the upper coarser ones, which is desirable. This is because the upper meshes, being nearer the suspension eyelet *k*, move in a circle of less diameter than the lower ones. As is known, sifting mesh of a fine weaving requires a more intense agitation than the coarser kind. Due to this fact, the reciprocating motion, hitherto imparted to the sifting boxes, resulted in the sifting in the fine mesh being incomplete when that in the coarser mesh was finished. Owing to the oscillatory suspension of the sifting box according to the present invention, and the more intense shaking of the lower meshes consequent upon this, the time of sifting is practically the same for both the coarse and fine meshes.

In order to keep the friction between the stops *n* and the enclosing rings *o* as low as possible the latter may be given a loose insertion *u* (Fig. 3) which is taken along during each impact of a stop, as long as the latter rolls over the ring *o*.

The gear casing may also be equipped with a revolution counter of any kind and if need be this, after a definite number of revolutions of the driving spindle *b*, may sound a bell signal or automatically switch off the drive.

The present invention is of course not restricted to sifting boxes but is suitable also for all kinds of other sifting and mixing purposes.

What I claim is:

1. A shaking device having a sifting receptacle, a carriage for the same, a vertical rotary shaft from which the said carriage is pendulously mounted, a plurality of striking means at the bottom of said carriage spaced round the periphery thereof, a stationary encircling ring surrounding the said striking

means and adapted to be impulsively engaged thereby when the base of said carriage swings outwards and means for driving said shaft about a vertical axis.

2. A shaking device having a sifting receptacle, a carriage for the same, a vertical rotary shaft from which the said carriage is pendulously mounted, the point of suspension thereof being eccentric to the axis of said shaft, a plurality of resilient striking means situated at the bottom of said carriage and spaced around the periphery thereof, a stationary resilient ring surrounding said striking means at a distance, its inner face adapted to be impulsively engaged thereby when the base of said carriage swings outwards and means for rotating said vertical shaft.

3. A shaking device comprising a sifting receptacle, a carriage for the same comprising a table freely suspended from a frame, a clamping device of variable height for fixing receptacles of different height on said table, a vertical rotary suspension shaft for said frame, a plurality of buffers round the periphery of said table, an impact ring encircling said buffers at a distance and adapted to be struck by said buffers during the revolution of said frame and means for imparting rotary movement to said shaft.

In testimony whereof I affix my signature.

RUDOLF PAWLICKOWSKI.
